UNITED STATES PATENT OFFICE.

EUGENE L. SCHELLEN, OF POINTE CLAIRE, QUEBEC, CANADA, AND JOEL S. COFFIN, JR., OF LISBON, NEW HAMPSHIRE, ASSIGNEES, BY MESNE ASSIGNMENTS, TO C-S ENGINEERING COMPANY, A CORPORATION OF DELAWARE.

LOCOMOTIVE DRAFT APPLIANCE.

Application filed May 16, 1925. Serial No. 30,734.

This invention relates to draft improvements in locomotives, particularly to those using rotary draft creating appliances, such as set forth in our co-pending application, 5 Serial No. 681,450 filed December 18, 1923.

The nature, objects and advantages of our invention will be best understood from the following.

In the operation of locomotives it is often 10 the case that the throttle is opened too wide for a certain speed and cut-off with a consequent increase in draft, eventually resulting in opening of the engine pops and a waste of steam and overspeeding the fan. 15 Also the fact that the standard fixed orifice nozzle employed is a compromise, in that it creates a draft blast which is an intermediate between the draft required for low speeds and that required for high speeds, results, 20 under some operating conditions, in blowing the pops.

Furthermore when a draft fan is used to create the draft, such an appliance as the one above referred to, there is a tendency to 25 blow the pops.

The primary object of our invention is to overcome or minimize such wastage of live steam; and to overcome overspeeding.

With the foregoing and such other objects 30 and advantages as will hereinafter appear, the invention consists in the novel arrangement and combination of parts hereinafter set forth.

In the accompanying drawings illustrating 35 the invention,

Fig. 1 is a diagrammatic side elevation of a locomotive showing the application of our improvements thereto, certain of the parts being broken away, and

Fig. 2 is an enlarged sectional view of the 40 pressure relieving valve and control mechanism.

Referring now to Fig. 1, the reference character A indicates the locomotive boiler, B 45 the fire box, C the front end or smoke box, D the draft appliance, E the draft appliance pressure relieving valve and F the locomotive throttle.

The draft appliance D is supplied with 50 exhaust steam from the locomotive valve chest 7 thru the conduit 8 leading into the fan steam chest 9, which steam constitutes the power medium for rotating the fan 10.

An annular space 11 is provided around the fan for the waste products of combustion, 55 from whence they discharge through the discharge outlet 12.

The fan steam chest 9 and the annular space or discharge chamber 11 have a connection 13 therebetween provided with a pressure relieving or by-pass valve 14, very similar in construction to an ordinary pop valve.

When the engine is operating and the live steam pressure approaches the value at which the locomotive pops would open, the pressure 60 relieving valve 14 opens, in the manner hereinafter described, whereby fan operating steam is by-passed from the fan chest 9 to the discharge chamber 11, thus reducing the 65 draft created thereby, preventing undue increase in the steam pressure and preventing 70 opening of the pops and overspeeding the fan.

The valve 14 is also controlled by a supplementary pilot valve 15 consisting of a 75 body 16 in which is slidably carried a spring-pressed follower member 17 pressing on the button head 18 of a plug valve 19. The tension of the follower member spring may be altered by the set screw 20, it being set at 80 a pre-determined pressure to admit steam to the under side of the plug valve 21 for lifting the valve 14.

Live steam is admitted at 22 to the bottom of the plug valve 19 by means of the 85 pipe connection 23 leading from the boiler of the locomotive, and when the steam admitted reaches a pressure to overcome the tension of the follower spring, the port 25 is uncovered and such steam passes by means of pipe connection 26 to the underside of the plunger 21. 90

The by-pass or pressure relieving valve 14 has a downwardly extending stem or spindle 27, the lower end of which carries a piston 28 mounted in the cylinder 29. The piston 95 28 is normally held in its lower position by means of a spring 30 between it and an adjusting nut 31 by means of which the tension of the spring may be adjusted to any predetermined amount.

Thus it will be seen that when the pressure on the underside of the plunger 21 reaches a point to overcome the tension of the spring 30 the valve 14 will be lifted from 100 its seat to function as previously described, 105 by reason of the stem 27 being in the path

of the plunger 21. Condensate accumulates in the cylinder 29 so that the piston 28 will normally operate under water giving a dash pot effect. The cavity 32 around the plunger 21 vents to atmosphere to prevent live steam from the pipe 26 from entering the dash pot.

We claim:

1. In a locomotive, the combination of a draft creating fan operated by exhaust steam, exhaust steam pressure relieving means, and automatic control means therefor, operating to reduce the speed of the fan including a steam connection leading from the source of live steam, said control means being responsive to the pressure of the live steam when it reaches a predetermined value.

2. In a locomotive, the combination of a draft creating fan operated by exhaust steam, a steam chest for the fan, a fan discharge chamber for the waste products of combustion, and means for by-passing some of said operating exhaust steam from said chest to said chamber when the boiler pressure reaches a predetermined value.

3. In a locomotive, the combination of a draft creating fan operated by exhaust steam and automatic means for by-passing some of said operating exhaust steam when the steam pressure reaches a predetermined value.

4. In a locomotive, the combination of a draft creating fan operated by exhaust steam and having a steam chest and a discharge chamber for the waste products of combustion; a pop valve controlled by-pass connecting said chest and chamber and automatic control means for said pop valve including a steam connection leading from the source of live steam.

5. In a locomotive, the combination of a draft creating fan operated by exhaust steam and having a steam chest and a discharge chamber for the waste products of combustion; a pop valve controlled by-pass connecting said chest and chamber and automatic control means for said pop valve including a steam connection leading from the source of

live steam, together with dash pot means for the pop valve.

6. The combination of a locomotive having a draft fan, and means operating to prevent overdraft by said fan, said means being responsive to a rise beyond predetermined values, respectively, of either the exhaust or live steam pressure of the locomotive.

7. In combination with a locomotive steam-actuated fan draft mechanism, a relief valve for the fan steam supply having yieldingly resistive means maintaining it normally in closed position but permitting it to open under the influence of the steam when the pressure thereof exceeds a predetermined value, together with means operating to open the valve upon a rise in the locomotive boiler pressure beyond a predetermined point.

8. In combination with a locomotive steam-actuated fan draft mechanism, a relief valve for the fan steam supply having yieldingly resistive means maintaining it normally in closed position but permitting it to open under the influence of the steam when the pressure thereof exceeds a predetermined value, together with means associated with the valve stem and operating to open the valve upon a rise in the locomotive boiler pressure beyond a predetermined point.

9. In combination with a locomotive steam-actuated fan draft mechanism, a relief valve for the fan steam supply having yieldingly resistive means maintaining it normally in closed position but permitting it to open under the influence of the steam when the pressure thereof exceeds a predetermined value, together with means operating to open the valve upon a rise in the locomotive boiler pressure beyond a predetermined point, said latter means including a piston bearing against the valve stem and means for delivering live steam thereto.

In testimony whereof, we have hereunto signed our names.

EUGENE L. SCHELLENS.
